PUMP

David P. Davies, Racine, Wis., assignor to J. I.
Case Company, Racine, Wis., a corporation

Application January 10, 1934, Serial No. 706,020
Renewed October 7, 1936

10 Claims. (Cl. 103—175)

My present invention relates to pumps of the centrifugal type employed for various purposes, and particularly for forming part of the circulating system of liquid cooled internal combustion engines, my object being to eliminate the use of fibrous packing and glands for preventing leakage, which type of devices, so far as I am aware, are difficult to maintain in constantly effective relation with associated parts. A further object 5 is to provide an improved and simplified structure which will obviate difficulties common to this type of pump from passage of water and gritty substances into its working parts to cause them to become quickly worn and distorted and therefore 10 inoperative so that frequent replacement of parts or a complete pump becomes necessary, as will hereinafter more fully appear, this being a continuation in part of my application Serial No. 595,678, filed February 29, 1932.

20 In the accompanying drawing, which forms a part hereof, Figure 1 is a transverse section through an engine-block and pump illustrative of my improvement; Fig. 2 is a sectional view taken on the dotted line 2—2 in Fig. 1, and Fig. 3 is a 25 detail view showing the relation of the impeller hub to the shaft and bushing when the latter has become worn.

In said drawing the numeral 5 indicates a jacketed engine-head having an outlet 6 leading 30 therfrom for returning water to a radiator (not shown), 7 an engine-block, 8 a cylinder wall, and 9 a piston, all of which parts are or may be of any desired construction and arrangement, the block 7 preferably embodying or having secured 35 thereto an apertured flange 10 terminating at its lower end in an intake 11 communicating with a supply pipe 12 extending from the radiator, said block and flange being spaced apart to form a water jacket 7.

40 In the application of my improved pump to an engine, for example, I mount in flange 10 a pump housing 14 having ports 15 therein which communicate with the channel 16 formed by the flange, said housing comprising a unitary structure 45 extending laterally from the flange and reduced in thickness through its outer portion to form a shoulder 17 and an internal flange 18, the latter dividing the housing into chambers 19 and 20 for a purpose to appear. In the bearing 50 portion 14' of housing 14 I insert a bushing 21 having a flange 22, which bushing preferably embodies an interior circumferential recess or channel 23 communicating with a similar channel 23' in said bearing; and in assembling the pump an 55 impeller comprising blades 24 and a shaft 25 em-

bodying an opening 25' therethrough converging from its opposite sides is mounted in the housing 14, the shaft 25 extending beyond the outer end thereof. The blades forming part of the impeller may be integrally formed with or connected to 5 an open-ended hub 26, having a closed end 26', extending into water jacket 7', which hub is suitably secured to the shaft 25 by a pin 27, and preferably extends into the housing 14, the adjacent ends of the hub and bearing being at right angles 10 in relation to the shaft, and which hub may be spaced from the bushing flange 22 by a washer 28 preferably of hardened material. As shown in Fig. 1, a lubricant supplying device 30 is inserted through an aperture 30' in housing 14 leading to 15 the channels 23' and 23, by which means shaft 25 may be efficiently lubricated. Within the outer end of housing 14 the shaft 25 is mounted in an anti-friction bearing 31 between which bearing and the flange 18 an expansion spring 32 is retained, said shaft and bearing being axially movable together. A hub 34 is mounted on the outer end of shaft 25, and is provided with fan blades 35, said hub and blades being of any desired construction and arrangement, and which hub may 20 be provided with or embody a pulley or other device 36, 37, for accommodating a preferably V-shaped belt 38 driven from a suitable source of power (not shown), the fan-hub 34 being secured to shaft 25 by a key 39 for rotating the same and 25 consequently the impeller blades 24 attached to said shaft, and a felt oil retaining ring 40 is preferably mounted about said hub 34 and secured in position on housing 14 between disks 40' by screws 41 or otherwise. The housing 14 when applied to 30 a structure as illustrated is secured to flange 10 by a series of bolts 42 by which means the housing, impeller, fan and associated parts when assembled may be installed or removed as a unit; and while I have described the pump in connection 35 with an engine, I desire it to be understood that the housing thereof may be employed with any suitable support.

40 It will be noted, Fig. 1, that the hub 26, having the closed end 26' for excluding fluid from shaft 45 25, is open at its opposite end and loosely fitted on said shaft and is therefore capable of variable movements thereabout, which mounting in practice I have found to be of advantage and importance, for the reason that where inequalities in 50 the face of the washer or bushing exist from faulty machining or wear, or misalignment of the shaft and bushing occurs through wear of either or both, the loose pivotal mounting of the impeller permits it to oscillate and become self- 55

adjusted so that its face will be brought to a fluid-tight fit against the washer or bushing at all times irrespective of the wearing of either the shaft 25 or bushing 21. It will be understood 5 that wear and misalignment of the bushing and shaft are principally caused by the downward pull of the belt 38 on the fan structure 34—35 on the outer end of the shaft, which imparts to the opposite or inner portion of the shaft a 10 tendency to be thrust upwardly and which force develops wear of the bushing or shaft or both at a longitudinal inclination substantially as indicated at *a* and *b* in Fig. 3, so that the finished face of the open end of hub 26, if said hub was 15 rigidly secured to the shaft, would gradually depart from the right angled relation thereto indicated in Fig. 1 and be so positioned at an incline in relation to the washer or bushing as to destroy the parallelism or full bearing of the parts, 20 and the hub face so angularly spaced as to cause leakage of fluid into the shaft. However, by providing the loosely mounted self-adjusting impeller 24 it will be seen that the constant outward axial thrust of shaft 25 will cause the loosely 25 mounted oscillating hub 26 to so adjust itself as to engage its face flush with and maintain the washer in fluid-tight relation between the end of said hub and bushing 22 in the right angled relation shown in Fig. 3, whereby any wear of 30 the shaft or bushing will be compensated for by the follow-up adjustment of the impeller in the manner stated. The loose fitting referred to is produced by the novel connection between the shaft and hub by means of the pin 27 passing 35 transversely through the shaft in the tapered opening 25' provided therefor and permitting its variable movements therein. By this means the hub will seat itself so that its face will be fully engaged in parallel relation with the thrust 40 washer 28, or the end of a longer bushing when the washer is omitted, and, therefore, these parts constantly wear tightly in flush relation to each other and prevent leakage of fluid about shaft 25 when wear occurs either on the shaft or bushing, 45 so that with the closed hub and the oil seal described, together with the outward axial thrust of the shaft either when rotating or idle, the combined elements are so engaged as to maintain the bearings and shaft leakproof from fluid and 50 foreign matter contained therein and thus preserve the parts from untimely wear.

In operation, it will be understood that the radiator fan and impeller are rotated together and that water from the radiator conveyed by the 55 hose or pipe 12 into the intake 11 is discharged into the channel 16 of flange 10 and passes through ports 15 and out between the impeller blades 24, by which blades the water is forced at high pressure through the water jacket 1' of 60 the engine-block and the jacketed engine-head 5, and thence through the outlet 6 and returned to the radiator, so that a continuous circulation of water for engine cooling purposes is set up in a well known manner. As shaft 25 is rapidly 65 rotating the thrust due to the angularity of fan blades 35 co-acting with the expansion of spring 32 against flange 18 and the bearing 31 constantly urges the shaft longitudinally in the direction of said fan 35, thus causing a fluid-tight 70 fit between the face of hub 26 and bushing 22, or when a washer, as 28, is interposed between the hub and bushing the same result is attained, but, as will be apparent, when the bearing is of sufficient length and of suitable material to form 75 a fluid-tight joint between its meeting end or

shoulder and the face of the hub, the interposition of other elements therebetween may be dispensed with. As will be understood, however, when in operation the fan thrust is sufficient to normally maintain the impeller hub and bushing in contact with a fluid-tight seal, but when shaft 25 and consequently blades 35 cease rotation or when the fan is removed for some purposes, the spring 32 alone will then effectively function to accomplish the same result. It will also be understood that the exclusion of water and other matter is further assured by the action of the rotating closed hub 26 which creates sufficient centrifugal force to prevent the entrance of water or other matter between the hub and bushing and also from entering between the bushing and the shaft 25. Therefore, as indicated, water and particles of foreign matter are prevented from passing between the meeting faces of the ends of the hub and bushing and 15 also between the bushing and the shaft, and no abrasive action will be created either upon the shaft itself or the bushing, so that abnormal wear of said parts will be obviated and the shaft thus maintained in proper relation to the bushing and the constant accurate assemblage and 20 preservation of said parts against wear prolonged indefinitely; and in order to provide ample lubrication for the shaft and parts associated therewith the chambers 19 and 20 are packed with 25 suitable material for the purpose, which, with the supply from the device 30, I have found in practice to at all times plentifully lubricate said shaft and associated parts. The lubricant supplied by said device 30 to the recesses or channels 23' and 23 is forced thereto under pressure so that an effective grease seal is established 30 against seepage of any small amount of fluid between the hub and shoulder towards the fan because of defective material or otherwise when 35 rotation of the fan ceases, and it will be understood that, should a bushing be dispensed with, a channel as 23', as shown, will produce an efficient grease seal in the manner stated.

In the manner disclosed I provide a pump structure embodying a housing and associated parts which assure a fluid-tight fit of the impeller and exclude foreign matter from the shaft thereof and its bushing or the equivalent of the latter, the admission of which is highly detrimental and 50 results not only in rapid wear but renders a pump of this type defective or wholly inoperable within a comparatively short space of time as indicated, in actual use I have demonstrated that pumps constructed as described by me overcome the 55 difficulty pointed out, and, therefore, frequent replacements of parts or renewal of a pump in entirety are eliminated, at material saving in expense usually incident to and necessary for the maintenance of such equipment, particularly the 60 type employing packing of fibrous material, which, as is well known, leaks at times, and to properly function must be retightened, but when no further retightening is possible to prevent leakage the renewal of such character of packing 65 becomes necessary.

I claim as my invention:

1. In a pump, a housing including a fluid receiving channel communicating with and discharging into an engine water jacket, said housing embodying a shaft bearing; a lubricant containing chamber forming part of said housing; means in the housing for retaining a spring; a spring in said retaining means; a shaft in the housing extending through the spring, lubricant 75

- 5 container and bearing and cooperating with the container to lubricate the bearing; an impeller on the inner end of the shaft including a hub having a closed end extending into the water jacket and an open end coacting with the adjacent wall of the shaft bearing to prevent leakage between the shaft and hub; means flexibly connecting the shaft and impeller hub whereby the face of the hub will become adjusted in fluid-tight relation to the bearing; an anti-friction bearing on the shaft engaged by and cooperating with the spring to thrust the shaft axially for engaging the hub and housing in fluid-tight relation; and means for rotating the shaft.
- 10 2. In a pump, a housing including a fluid-receiving chamber and a bearing having a channel associated therewith for producing a seal about a shaft, said chamber communicating with and discharging into an engine water jacket; a shaft in the bearing; an impeller on the inner end of the shaft including a hub having a closed end extending into the water jacket and an open end coacting with the adjacent wall of said bearing to prevent leakage between the shaft and hub; means flexibly connecting the shaft and impeller whereby the face of the impeller hub will become adjusted in fluid-tight relation to the housing; means for supplying lubricant to the bearing channel for forming a grease seal circumferentially of the shaft; and means in the housing associated with the shaft for thrusting the latter axially for engaging the hub and housing in fluid-tight relation.
- 15 3. In a pump, a housing embodying a ported channel communicating with and discharging fluid into an engine water jacket and also forming a shaft bearing; a shaft in the bearing; an impeller on the inner end of the shaft including a hub having a closed end extending into the water jacket and an open end cooperating with the adjacent wall of said bearing to prevent leakage between the shaft and hub; means flexibly connecting the hub and shaft whereby the face of the hub will become adjusted in fluid-tight relation to the housing; means engaging the housing and anti-friction bearing to thrust the shaft outwardly when rotating and also for urging the shaft in the same longitudinal direction when non-rotating to maintain the meeting ends of the impeller hub and housing in fluid-tight relation.
- 20 4. In a pump, a housing forming a shaft bearing having means associated therewith for producing a grease seal about a shaft, said housing communicating with and discharging fluid into an engine water jacket; a shaft in the housing extending through the bearing; means associated with the housing for introducing lubricant therethrough to the shaft; an impeller on the inner end of the shaft including a hub having a closed end extending into the water jacket and an open opposite end coacting with the adjacent wall of said bearing to prevent leakage between the shaft and hub; means flexibly connecting the hub and shaft whereby the face of the hub will become adjusted in fluid-tight relation to the housing; means in the housing and concentric with the shaft forming with the housing a lubricant containing chamber cooperating with the shaft to lubricate said bearing; an anti-friction bearing on the shaft; a driving pulley on the outer end of the shaft; means for rotating the pulley to actuate the shaft; and yielding means engaging the housing and anti-friction bearing to thrust the shaft outwardly when rotating and also for urging the shaft in the same longitudinal direction when non-rotating to maintain the meeting ends of the impeller hub and housing in fluid-tight relation.
- 25 5. In a circulating pump for an engine having a water jacket, a pump housing including a bearing therein, a pump shaft journaled in said bearing, an impeller arranged at one end of said housing and having a hub presenting an open end to said housing, a closure spaced from said housing to provide a chamber within said hub closed against entrance of fluid and into which said shaft extends, means connecting said hub and said shaft and arranged to allow universal angular movement and also to prevent substantial axial movement therebetween, and means arranged to continuously urge said shaft axially in a direction to maintain the open end of said hub in continuous fluid-sealing contact with said housing about said shaft to prevent entrance of fluid between the hub and said housing, or between said shaft and said bearing.
- 30 6. In a circulating pump for an engine having a water jacket, a pump housing including a bearing therein, a pump shaft journaled in said bearing, said bearing providing a recess therein for retaining a quantity of lubricant in contact with said shaft, an impeller arranged at one end of the housing having a hub presenting an open end to said housing and also having a closure spaced from the housing to provide a chamber within the hub, closed against entrance of fluid from said water jacket, and into which said shaft extends, means connecting said hub and said shaft and arranged to allow universal angular movement but to prevent substantial axial movement therebetween, means arranged to continuously urge said shaft axially in a direction to maintain the open end of said hub in continuous fluid-sealing contact with said housing about said shaft, and means for introducing lubricant under pressure into said recess for producing a film of lubricant between the shaft and bearing and also between the hub and said housing for assisting in forming a fluid-tight seal between said water jacket and the shaft.
- 35 7. In a pump, a housing including a fluid receiving chamber adapted to communicate with and discharge into an engine block, said housing embodying a channeled bearing for producing a seal about a shaft; a shaft in the bearing; an impeller on the inner end of the shaft including a hub embodying a closed end presented to the engine block for preventing entrance of fluid from the latter to the shaft and an open end cooperating with said bearing to prevent leakage between the shaft and hub; means flexibly connecting the shaft and impeller hub whereby the latter will move in variable relation to the shaft so that the open end of the hub will become self-adjusted in fluid-tight relation to the bearing; and means in the housing associated with the shaft for thrusting the latter axially to engage the hub and bearing in fluid-tight relation.
- 40 8. In a pump, a housing including a fluid receiving chamber adapted to communicate with and discharge into an engine; a shaft in the housing; an impeller on the inner end of the shaft including a hub embodying a closed end presented to the engine for preventing entrance of fluid from the latter to the shaft and an open

- end cooperating with said housing to prevent leakage between the housing and hub; means loosely connecting the shaft and impeller hub whereby the latter will move in variable relation to the shaft so that the open end of the hub will become self-adjusted in fluid-tight relation to the housing; and means in the housing associated with the shaft for thrusting the latter axially to engage the hub and housing in fluid-tight relation. 5
9. In a pump, a housing including a fluid receiving chamber adapted to communicate with and discharge into an engine; a shaft in the housing; an impeller on the inner end of the 10 shaft including a hub embodying a closed end presented to the engine for preventing entrance of fluid from the latter to the shaft and an open end cooperating with said housing to prevent leakage between the housing and hub; means 15 loosely connecting the shaft and impeller hub whereby the latter will move in variable relation to the shaft so that the open end of the hub will become self-adjusted in fluid-tight relation to the housing; and means in the housing remote from the hub and associated with the shaft for thrusting the latter axially to engage the hub and housing in fluid-tight relation. 5
10. In a rotary pump a pump housing including a bearing, a discharge chamber, a pump shaft journaled in said bearing, an imperforate impeller arranged at one end of said housing to communicate with the discharge chamber, said 10 housing providing a sealing surface presented toward said discharge chamber and surrounding said shaft, said impeller having a complementary surface engaging said sealing surface in sealing relation thereto, a connection between said impeller and said shaft arranged to provide freedom from angular movement but preventing relative axial movement therebetween, and means for continuously urging said shaft in a direction 15 to force said complementary surface against said sealing surface. 20

DAVID P. DAVIES.
